(57) **CLAIM**

The ornamental design for a bottle, as shown and described.

DESCRIPTION

1. Bottle

1.1 : Perspective

1.2 : Front

1.3 : Back

1.4 : Right

1.5 : Left

1.6 : Top

1.7 : Bottom

The design is for a bottle for water or other liquids; the design comprises a plurality of grooves extending from the neck of the bottle towards the bottom of the bottle; the grooves are substantially parallel to each other near the neck of the article, and undulate as they progress from top to bottom; each groove undulating generally in the opposite direction to the adjacent groove, and the top of the grooves being wider than the bottom of the grooves. Figure 1.1 is a perspective view of the bottle; Figure 1.2 is a front view of the bottle; Figure 1.3 is a rear view of the bottle; Figure 1.4 is a side view of the bottle; Figure 1.5 is an alternative side view of the bottle; Figure 1.6 is a top view of the bottle; Figure 1.7 is a bottom view of the bottle.
